UNITED STATES PATENT OFFICE.

JOHN EDWARD BANNER, OF MOUNT AIRY, NORTH CAROLINA.

STAGE-DAGGER.

1,016,727.

Specification of Letters Patent.

Patented Feb. 6, 1912.

Application filed January 21, 1911. Serial No. 603,957.

To all whom it may concern:

Be it known that I, JOHN E. BANNER, a citizen of the United States, and a resident of Mount Airy, county of Surry, and State 5 of North Carolina, have invented certain new and useful Improvements in Stage-Daggers, of which the following is a full and clear specification, reference being had to the accompanying drawings, in which—

10 Figure 1 is a side elevation partly broken away at the handle portion; Fig. 2 a transverse section on the line 2—2 of Fig. 1; and Fig. 3 a perspective view of the blade detached.

15 The object of this invention is to so construct the weapon that it may be used by the actor in a natural and realistic manner without injury to the actor assaulted, thereby avoiding the detracting effects of the non 20 realistic exhibitions of dagger and stiletto stage assaults as now rendered with the real or stage daggers now in general use on the stage, as more fully hereinafter set forth.

25 My device in its preferred form consists of a blade *a* of any suitable length and cross section and provided at its point with a flexible point section *b*, this section *b* consisting of a piece of flexible rubber or other material having the shape of the point of the blade 30 and being sufficiently flexible to bend or turn when it is pressed against the body of the person assaulted with the weapon. At the butt end of the blade it is provided with a cylindrical head or extension *c* having a 35 diameter greater than the blade measuring the same flat-wise and less than the blade measuring the blade from edge to edge, thus forming lateral shoulders *d* coincident with the butt end of the blade. This extension *c*

40 works in a central longitudinal passage formed centrally in the handle *e*, and the shoulders *d* normally abut against the guard *f* on the forward end of the handle. The opening in the guard *f* is of the same shape 45 as the cross section of the blade, and the butt end of the blade normally rests in said opening, a spiral spring *g* located in the hollow handle being employed to normally project the blade to its operative position and to 50 hold the shoulders *d* against the inner face of the guard *f*. The spring *g* is inclosed in the hollow handle and its rear end abuts against a cap *h* screwed removably to the rear end of the handle. Longitudinal grooves

i are formed at opposite sides of the passage 55 through the handle to receive the longitudinal edges of the blade when the same is pressed back into the handle.

It will be observed that when this weapon is grasped by the handle and the blade is 60 thrust against the body of the actor being assaulted, the spring will yield and permit the blade to recede back into the handle, and when the weapon is drawn away from the body the spring will instantly return the 65 blade to its projected position and thus give the appearance of being withdrawn from the body of the mimic victim. The flexible tip prevents the initial impact of the blade against the body of the actor from causing 70 even the slightest abrasion. By making the cap at the upper end of the handle removable, it will be observed that the parts may be readily assembled and also taken apart.

It will be observed that the head *c*, serves 75 to guide the blade in its reciprocating movements and to hold it in proper position when the blade is projected. It will be understood that the flexible tip of the blade may be silvered or otherwise colored to give it the 80 appearance of being an extension of the metal part of the blade.

It will be obvious that the flexible tip may be attached to the blade in any suitable manner; I have shown it attached to the blade 85 by forming a tenon *b'* upon its butt end and provided with a socket in the end of the blade for the tenon, suitable cement or other means being employed to fasten the tenon in the socket.

Having thus described my invention, what I claim as new and desire to secure by Letters Patent, is—

A stage weapon of the dagger or stiletto type, consisting of a handle, a blade and 95 means for normally projecting it and allowing it at all times to recede back its full length into the handle, said blade being provided with a flexible and bendable tip or point having normally the shape of a continuation of the blade.

In testimony whereof I hereunto affix my signature in the presence of two witnesses.

JOHN EDWARD BANNER.
